[57] CLAIM

The ornamental design for the head mounted display system, as shown and described.

DESCRIPTION

FIG. 1 is a front and right side perspective view of the head mounted display system showing our new design, the opposite side being a mirror image except for the two offset central elements seen in the front view;
FIG. 2 is a top view of the head-up display system of FIG. 1;
FIG. 3 is a front view of the head-up display system of FIG. 1; and,
FIG. 4 is a front view of an alternative embodiment of the head-up display system of FIG. 1 having a split lens.
The rear and bottom of the head mounted display system forms no part of the claimed design.
